(57) **CLAIM**

The ornamental design for a flat top electronic pillar candle with a matrix flame, as shown and described.

DESCRIPTION

FIG. 1 is a front view of the flat top electronic pillar candle with a matrix flame of the present disclosure;

FIG. 2 is a rear view of the flat top electronic pillar candle with a matrix flame of FIG. 1;

FIG. 3 is a side view of the flat top electronic pillar candle with a matrix flame of FIG. 1;

FIG. 4 is a top view of the flat top electronic pillar candle with a matrix flame of FIG. 1;

FIG. 5 is bottom view of the flat top electronic pillar candle with a matrix flame FIG. 1;

FIG. 6 is a perspective view of the top of the flat top electronic pillar candle with a matrix flame of FIG. 1; and,

FIG. 7 is a perspective view of the bottom of the flat top electronic pillar candle with a matrix flame of FIG. 1.

The broken lines of FIGS. 2-5 and 7 are provided for purposes of illustration and form no part of the claimed design of the present application. However, the broken lines are intended to provide explicit disclosure as to presently unclaimed portions of the design, and Applicant reserves the right to pursue and claim such other presently unclaimed portions in one or more continuation applications.

1 Claim, 6 Drawing Sheets
